DESIGN FOR A BEDSTEAD

Leo Jiranek, Scarsdale, N. Y., assignor to Heywood-Wakefield Company, Gardner, Mass., a corporation of Massachusetts

Application March 3, 1941, Serial No. 99,324

Term of patent 7 years

To all whom it may concern:

Be it known that I, Leo Jiranek, a citizen of the United States and a resident of Scarsdale, county of Westchester, and State of New York, have invented a new, original, and ornamental Design for a Bedstead, of which the following is a specification, reference being had to the accompanying drawing, forming a part thereof, in which Fig. 1 is a perspective view of a bedstead, showing my new design. Fig. 2 is a top plan view of the head end of the bedstead. Fig. 3 is a top plan view of the foot end of the bedstead. Fig. 4 is a fragmentary vertical sectional

view on an enlarged scale through a part of the head end of the bedstead as taken on the line 4—4 of Fig. 1. Fig. 5 is a fragmentary vertical sectional view through a part of the foot end of the bedstead on the scale of Fig. 4 as taken on the line 5—5 of Fig. 1. Fig. 6 is a fragmentary horizontal sectional view through a part of the foot end of the bedstead also on the scale of Fig. 4, as taken on the line 6—6 of Fig. 1.

I claim:

The ornamental design for a bedstead, substantially as shown.

LEO JIRANEK.
